UNITED STATES PATENT OFFICE.

BRUNO VON BÜLTZINGSLÖWEN, OF NEW YORK, N. Y., ASSIGNOR OF ONE-HALF TO THEODOR SAUER, OF NEW YORK, N. Y.

MACHINE FOR BENDING CROSS-HEADS AND EYES OF WIRE BALE-TIES.

SPECIFICATION forming part of Letters Patent No. 752,513, dated February 16, 1904.

Application filed April 16, 1902 Serial No. 103,199. (No model.)

To all whom it may concern:

Be it known that I, BRUNO VON BÜLTZINGSLÖWEN, a citizen of the Empire of Germany, residing in New York, borough of the Bronx, and State of New York, have invented certain new and useful Improvements in Machines for Bending the Cross-Heads and Eyes of Wire Bale-Ties, of which the following is a specification.

This invention relates to certain improvements in machines for bending the cross-heads and eyes of wire bale-ties; and the object of this invention is to produce the bending of the cross-head or eye by foot-power and then impart a rotary motion to the bending devices on their axes for a predetermined number of times for twisting the shank of the cross-head or eye without transferring the bale-tie to a separate twisting mechanism and for this purpose the invention consists, primarily, of mechanism for bending the end of the wire blank into the proper shape of the cross-head or eye and then automatically twisting the shank of the same by imparting rotary motion on their axes to the bending devices in connection with stationary clamping-jaws for holding the wire blank and the end of the cross-head or eye, the bending operation being performed by foot-power, while the twisting of the shank of the cross-head or eye is performed automatically by steam or other power.

The invention consists, further, of the combination of the bending devices for the ends of the wire bale-tie with clamping devices for holding the body of the wire and the shank of the cross-head or eye firmly in position and of twisting devices operated from the driving-shaft for imparting immediately on the completing of the cross-head or eye the necessary twisting motion to the shank of the same, as will be fully described hereinafter and finally pointed out in the claims.

In the accompanying drawings, Figure 1 represents a front elevation of my improved machine for bending the cross-heads and eyes of wire bale-ties, partly in section, through the supporting bed-plate. Fig. 2 is a plan view of Fig. 1. Fig. 3 is a vertical longitudinal section through the upper part of the

machine, the wire-bending devices being omitted. Figs. 4 and 5 are vertical transverse sections respectively on lines 4 4 and 5 5, Fig. 1. Fig. 6 is a detail side elevation of the devices for bending the cross-head, partly in vertical section and showing the parts in position for inserting the wire blank. Fig. 7 is a similar view showing the parts in position after the cross-head is bent and before the twisting of the shank of the same. Fig. 8 is a vertical transverse section on line 8 8, Fig. 6. Fig. 9 is a side elevation of Fig. 8, showing the closing-plate of the bending mechanism moved into position for holding the cross-head in position after bending. Fig. 10 is a horizontal section on line 10 10, Fig. 6. Fig. 11 is an end elevation of the jaws for clamping the ends of the bent cross-head or eye preliminary to twisting the shank of the same. Fig. 12 is a side view of a completed cross-head. Figs. 13 and 14 are detail side elevations, partly in section, of the devices for bending the eyes on the wire bale-ties, the parts being shown, respectively, in position before bending and after bending the eye. Fig. 15 is a vertical longitudinal section on line 15 15, Fig. 13. Fig. 16 is a side view of the completed eye of a wire bale-tie; and Fig. 17 is a plan view showing a double machine for simultaneously bending and twisting a cross-head at the end of one wire blank and an eye at the end of another wire blank with mechanism for performing both operations at the same time, but in connection with two main shafts and wire-clamping devices.

Similar letters of reference indicate corresponding parts.

Referring to the drawings, A represents the table of my improved machine for bending the cross-heads and eyes of wire bale-ties. The table is supported on suitable standards, at the lower part of which the operating-treadle (not shown) is arranged.

H represents an elbow-lever which is fulcrumed to legs on the table A, the upper arm of the lever extending through a slot in the table A and being provided with a forked end having antifriction-rollers h, which engage a sliding sleeve c, that is splined to the main

shaft B. The main shaft B is supported in journal-bearings of upright standards F G, which are attached to the upper part of the table A. The lower arm of the elbow-lever 5 H is connected by a pivot-rod H' with the operating-treadle, which is held in raised position by a helical spring H², which is attached to the treadle and to the under side of the table A. The sleeve C is provided with 10 flanges at both ends, the left-hand flange having two diametrical ears c, from which project lugs c' at right angles to the ears c, to which are pivoted rods R R², which serve for the purpose of operating the cranks R' R³, 15 that are located, respectively, at opposite sides of the wire-bending mechanism. The main shaft B is provided at its end with a flattened head, as shown in Fig. 3, to which the bending mechanism for the cross-head or eye is attached. 20

The cross-head-bending mechanism consists of a plate P, which is secured to one side of the flat head and provided with a raised rim p³, that is recessed at its upper part for inserting the wire blank z. The parts for bending the end of the wire blank z are arranged on the inner surface of the plate P within the rim p³ of the same. In a bore of the plate P is arranged a pivot T, which passes through 25 the plate and the flattened head of the shaft B. On the end of the pivot T is mounted a bending-arm t², which carries at its outer end a pin t³, by which the end of the wire blank z is bent over toward the body of the same. 30 In the center of the pivot T is arranged a stationary pin t, which serves to hold the wire blank during the bending operation in forming the cross-head or eye. A second pin t' is arranged on the bending-arm t², eccentrically 35 to the center pin t, so as to hold the wire during the bending operation without pressing the wire blank tightly against the center pin. Below the pivot T of the bending-arm t² is arranged in the plate P a second pivot T', on 40 which pivot is mounted the die V for bending the hook of the cross-head, said hook-bending die being provided with a recess and two noses v v', one at each side of the recess. Sidewise of the pivot T is arranged on the plate P a pin U, 45 which serves for supporting the wire blank z when the same is inserted in the upper recessed part of the rim p³ of the plate P and into a recess in the end of the main shaft B, as shown in Fig. 6. The bending-arm t² is operated by 50 means of gear-wheels S S², of which the gear-wheel S² is secured on the rear end of the pivot T, while the gear-wheel S is mounted on a pivot S³, which is journaled in bearings of the plate P and located in the same horizontal plane with the pivot T'. The forward motion of the sliding sleeve C operates by the rod R² the crank R³, and thereby the actuating-gears S S² of the bending-arm t², while 55 the rod R operates by the crank R' the hook-bending die V. The center pin t and pins t' 60

t³, located on the bending-arm t², as well as the pin U on the inner face of the plate P, project slightly beyond the rim p³ of the plate P, as shown clearly in Fig. 8. A counter-plate P' is loosely mounted upon the pivots 70 T' and S³ and shifted laterally toward the plate P during the bending operation imparted to the end of the wire blank, so that the ends of the pins t, t', t³, and U project into a suitable recess in the plate P' and retain the wire blank 75 against lateral displacement before the twisting operation commences. The laterally-shifting movement of the counter-plate P' is effected by two cam-surfaces p' p², of which the cam p' is arranged on the counter-plate P' 80 concentrically with the pivot T', while the cam p² is tightly secured to the pivot T'. As soon as the action of the cam-surfaces p' p² is interrupted the counter-plate P' is returned from the position shown in Fig. 9 into the position shown in Fig. 8 by means of two helical springs p⁵, which are placed on pins p⁴ of the counter-plate P', said pins being kept in position by means of sockets p, located in projections at diametrically opposite points of 85 the plate P, as shown clearly in Figs. 6 and 10. 90

Adjacent to the cross-head-bending devices and transversely thereto is arranged an upright bracket N, which is attached to the table A by means of suitable bolts, as shown in 95 Figs. 1, 2, 3, and 11. To the upper end of this bracket N is attached a laterally-projecting arm n, to which a clamping-block N' is pivotally connected. The clamping-block N' is connected by a rod N², which is guided in 100 a suitable opening of the table A and extended to some distance below the table. In the adjacent edges of the bracket N and the clamping-block N' are arranged small recesses n⁴ n⁵, which engage the body of the wire blank z 105 and the bent-over end of the cross-head, respectively, so as to hold them firmly in position for the twisting operation, the bracket N and the clamping-block N' serving as clamping-jaws for holding the shank of the cross-head in position. A cross-pin n' at the upper end of the clamping-jaw N' serves for holding the shank of the cross-head firmly in position of the recesses n⁴ n⁵. To the lower end of the rod N² is applied a transverse pin n², which 110 is actuated at the proper time by the free arm of a lever M, which is fulcrumed to the lugs a, attached to the under side of the table A, and which is provided with a roller m, which in the last part of the downward motion of 115 the fulcrumed lever M engages the transverse pin n' and moves the same in downward direction against the tension of a helical spring n⁸, which connects the under side of the table A with a pin on the lower end of the rod N², 120 as shown clearly in Fig. 1. The opposite end of the lever M is connected by a link L with the elbow-lever H, so that the fulcrumed lever M and the movable clamping-jaw N' are operated at the proper time by the elbow-lever 125 130

H and the connecting-rod H', operated by the foot-treadle.

The devices for bending the end of the wire blank z' in the shape of an eye are shown in Figs. 13 to 16. These bending devices are constructed similar to the devices for bending the cross-head, with the difference that the hook-bending die V is dispensed with. The supporting-plate P is attached to the flattened head of the main shaft B in the same manner as the plate P of the cross-head. The arm t^2 carries at its outer end the pin t^3 for bending the end of the wire blank, while the center-pin t is arranged in the pivot T, so as to serve as a support for the wire during the bending operation, which is assisted by the pin t' , arranged eccentrically on the pivot T, so as to hold the wire blank z' in position during the bending operation. A pin u is secured upon the inner face of the plate P for limiting the length of the eye. A recess in the bending-arm t^2 passes over the pin u when the end of the wire z' has been bent into shape of the eye, as shown in Fig. 14. For operating the bending-arm t^2 a gear-wheel S^2 is keyed to the pivot T and meshes with a gear-wheel S, that is secured to the pivot S^3 , which is supported by the plate P. On both sides of the pivot S^3 cranks R^1 R^2 are located, which are connected with the sliding sleeve C by means of shifting rods R^1 R^2 , respectively. A counter-plate P' is loosely mounted upon the pivot S^3 and kept in position of rest away from the plate P by means of helical springs, while it is pressed against the plate P by the movement of the sleeve C through the medium of the cam-surfaces p' p^2 , which turn upon each other, the cam-surface p^2 being in tight connection with the pivot S^3 . The pins t' and t^3 project beyond the rim of the plate P and enter a suitable recess of the plate P' when pressed against the plate P, so as to secure thereby the wire z' in position for the twisting operation.

The cross-head or eye bending devices are operated by the depression of the treadle by the foot of the attendant. As soon as the bending operation is accomplished the shanks of the cross-head or eye are firmly clamped by the jaws N N' and held in position ready for the twisting operation.

The twisting operation of the shank is accomplished by the following mechanism: On the main shaft B is mounted a loose pulley E, which may be thrown into operative connection with the main shaft B by a clutch device e. Immediately after the cross-head or eye is bent by the bending mechanism the pulley is clutched to the shaft B by means of a sliding sleeve D, which is loosely mounted on the main shaft B. The sliding sleeve D is operated by a lever K, which projects through an opening in the table A to some distance below the same. The upper forked end of the lever K engages the flanges at the ends of the sliding sleeve D by means of rollers K'. A

helical spring K³ connects the lower end of the lever K with the stationary arm on the under side of the table, so as to draw the lower end of the lever K toward the right, as shown in Fig. 1, and press a pin K² on the same against the face of a disk f', which is mounted at the end of a shaft f, that is supported in brackets F' G', which are attached to the under side of the table A. The disk f' is provided with a recess, which is engaged by the pin K² of the lever K. To the rear end of the auxiliary shaft f is applied a sprocket-wheel B², which receives rotary motion by a sprocket-chain from a sprocket-wheel B' on the main shaft B in the ratio of three to one. The power-transmitting mechanism described is put in operation by depressing the treadle, and thereby oscillating the elbow-lever H. The lower arm of the fulcrumed lever H is pivotally connected with a slotted link L', the slot of which is guided on a fixed pin projecting from a bracket a' at the under side of the table A. The opposite or lower end of the slotted link L' is pivotally connected with a rod L², which may be called a "ratchet-bar." This ratchet-bar L² engages a pin k on the lower end of the lever K, the pin k having a flattened upper face which serves as a support for the ratchet-bar L² when the machine is in a position of rest. The ratchet-bar L² has on its under side a recess, one side l of which is nearer to its pivot and is inclined toward the free end of the bar, while the opposite side runs approximately at right angles to this bar, so as to form one side of a tooth l², the outer side of which is also inclined toward the end l³ of the ratchet-bar L². The ratchet-bar L² is prevented from shifting laterally by a U-shaped keeper k', attached to the lower end of the lever K. When in moving the ratchet-bar L² the flattened pin k enters the recess of the angle-bar L², the tooth l² engages the pin k and moves the lever K into the position shown in dotted lines in Fig. 1, so that the pin K² is withdrawn from its socket in the disk f', while its upper end engages the clutch device e and imparts rotary motion to the shaft B for producing the motion of the shank of the cross-head. An angle-arm f'', which projects downwardly from the supporting bracket-arm F', serves as a support for the free end l³ during the forward movement of the bar L².

Fig. 17 shows the arrangement of a machine for producing simultaneously the cross-head at the end of one wire blank z and the eye at the end of a second wire blank z' by means of cross-head and eye bending devices, respectively, on two separate shafts B³, the shaft B³ carrying the eye-bending mechanism at its flattened head and having adjacent thereto a separate pair of clamping-jaws for tightly holding the end of the wire blank z' during the twisting operation, while a single clutch device is used for setting both

shafts of the machine in operation. The elbow-lever H, which operates the sliding sleeve C and shaft B, also shifts the sliding sleeve C on the shaft B³ by a connecting-arm H³. In the same way the uniform movement of the clamping-jaws is effected by a laterally-connecting bar N⁶, while the rotation of the shaft B is transmitted to the shaft B³ by means of sprocket-wheels B⁴ B⁵ on the free ends of the shafts B³ and B and sprocket-chains between said sprocket-wheels and between the shaft B and the auxiliary shaft f.

My improved machine for bending the cross-heads and eyes of wire bale-ties is operated as follows: After inserting the wire blank z, as shown in Figs. 1, 2, and 6, into position between the open clamping-jaws N N' and the bending devices the treadle is depressed, so that the elbow-lever H is placed by the connecting-rod H' in position shown in dotted lines in Fig. 1. By the oscillation of the elbow-lever H the sliding sleeve C is shifted on the main shaft B by the upper forked end of the elbow-lever H, so as to operate by the intermediate motion-transmitting mechanisms the bending-arm t² and the hook-forming die V and bend thereby the end of the wire blank into the shape of the cross-head, as shown in Fig. 7. The bending of the end of the wire blank around the pin t, which is solely effected by the action of the pin t³ upon the outer end of the bending-arm t² leaves sufficient play between the wire and the pin t for easily removing the finished cross-head, as pin t', being eccentrically arranged to the center pin in the pivot T, does not press the wire against the center pin t, but serves as an auxiliary support for the wire blank during the bending operation. A short time after the bending-arm t² has commenced its operation the hook-forming die commences to turn; but it does not act on the wire blank until the bending motion performed by the bending-arm is nearly completed, so as to prevent thereby any shifting and unusual strain on the wire blank when the hook-forming die commences its work. The object of preventing unnecessary tension in the cross-head is furthermore insured by the form of die V, the nose v of which enters first into operation. At the same time that the die V begins to turn the counter-plate P' is shifted laterally on the pivots T' and S³ by means of the cam-surfaces p' p², mounted, respectively, on pivot T' and the plate P' itself, as shown in Fig. 9. In this position the plates P P' thoroughly secure the wire blank and later on the finished cross-head, so as to prevent any lateral movement during the clamping and twisting operations.

The springs p⁵, being compressed by the lateral shifting of the plate P', effect the return of the latter into its normal position after the clamping-surfaces are released from each other. The clamping-jaws, by which the shanks of the cross-head are securely held in

position, so as to prevent any movement of the same during the twisting operation, are closed on the shank at the last moment of depression of the treadle through the medium of the link L, which is pivoted to the elbow-lever H and the double lever M, the motion of the latter being without effect until its free arm comes into contact with pin n² of rod N², so as to carry the same downward to the position shown in dotted lines in Fig. 1, thereby bringing the clamping-jaw N' toward the clamping-jaw N, and secure thereby the shank of the cross-head firmly in position, as shown in Fig. 11. As soon as the cross-head is finished and engaged by the clamping-jaws the clutch device e is thrown into engagement for transmitting rotary motion to the shaft B for producing the twisting of the shank of the cross-head. During the depression of the treadle the slotted link L', which is pivoted to the lower end of the arm of the elbow-lever H, is moved upwardly into the position shown in dotted lines in Fig. 1, thereby sliding and turning upon the pivot l', secured to the bracket a'. At the beginning of this movement the ratchet-bar L² slips upon the pin k and effects the movement of the lever K only at the moment when the tooth l² reaches and pulls the pin k, thus causing the pin K² to leave the recess in the disk f'. During the operation of bending the cross-head the lever K is turned upon its pivot, as there is some play between the lever K and the clutch device e. At the moment when the cross-head is finished and the clamping-jaws hold the shank of the cross-head the pin K² is released from its recess in the face of the disk f' and the clutch is thrown into engagement with the pulley E, thus rotating the main shaft B. By means of a sprocket-wheel transmission B' B² motion is transmitted in the relation of three to one to the shaft f' of the disk f'. As the ratchet-bar L² is supported at its outer end l³ by the angular rod f² in such a position as to allow the lever K to slip back, since the tooth l² is finally elevated above the flattened face of pin k, the lever K will return into its position of rest as soon as the disk f' has completed one full revolution, when pin K² will enter the recess in the disk f' without regard to the release of the treadle. The ratio in the transmission of power limits the rotation of the main shaft B to three rotations, so as to impart to the shank of the cross-head three twists and finish thereby the cross-head, as shown in Fig. 12.

The operation of the wire-bending devices for the eyes of bale-ties is shown in Figs. 13 to 16 and is nearly the same as the operation described for bending the cross-heads, only that the hook-forming die is removed. It requires, therefore, no further description. Either the wire-cross-head-bending devices or the eye-bending devices may be attached to the flattened head of the shaft B. The rods R R², operating the cranks R' R³ on the ends

of the pivot S^3 , and the intermediate gear-wheels produce the operation of the wire-bending arm t^2 . The latter completes its operation at the same time as the hook-forming device—that is to say, just before the rotation of the main shaft B begins. The counter-plate P' for securing the eye during the bending operation is pressed against the plate P in the same manner as that described for the cross-head-bending operation by means of cam-surfaces $p^1 p^2$.

The operation of the combined shafts $B B^3$ for forming a cross-head and an eye on wire bale-ties $z z'$ requires no further explanation.

15 By the double machine both a cross-head and an eye can be bent at the same time, one operation of the treadle, one clutch device, and one mechanism for limiting the number of rotations of the ends of the wire blanks only being necessary for actuating both bending and twisting devices.

Having thus described my invention, I claim as new and desire to secure by Letters Patent—

1. In a machine for bending the cross-heads and eyes of wire bale-ties, the combination of a shaft, a supporting-plate attached to the head of said shaft, a bending-arm pivoted to said supporting-plate and provided with a pin at its outer end, a center pin in the pivot of the bending-arm, a second pin on the bending-arm eccentrically to said center pin, a stationary pin on the supporting-plate, a treadle-operated sliding sleeve splined on said shaft, and means between said sliding sleeve and the pivot of the bending-arm for moving the latter on its pivot for bending the end of the wire blank into the shape of a cross-head or eye, substantially as set forth.

2. In a machine for bending the cross-heads and eyes of wire bale-ties, the combination of a shaft, a supporting-plate attached to the head of said shaft, a bending-arm pivoted to said supporting-plate and provided with a pin at its outer end, a center pin in the pivot of the bending-arm, a second pin on said arm eccentrically to said center pin, a stationary pin on the supporting-plate at the side opposite to the bending-arm, a sliding sleeve splined to said shaft, a crank-arm pivoted to said supporting-plate below the bending-arm, a link connecting said crank-arm with the sliding sleeve, and gear-wheels between the pivot of the crank-arm and the pivot of the bending-arm for imparting a rotary reciprocating motion to the bending-arm, substantially as set forth.

3. In a machine for bending the cross-heads and eyes of wire bale-ties, the combination of a shaft, a supporting-plate attached to the head of said shaft, a bending-arm pivoted to the supporting-plate and provided with a pin at its outer end, a center pin in the pivot of the bending-arm, a stationary pin on the supporting-plate at a point opposite to the bending-arm, a sliding sleeve splined to the shaft, motion-

transmitting mechanism between the sliding sleeve and the pivot of the bending-arm for imparting rotary reciprocating motion to the same, a hook-bending die pivoted to the supporting-plate below the bending-arm, said die being provided with two noses that pass at opposite sides of the stationary pin, and motion-transmitting mechanisms between the sliding sleeve and the pivot of the bending and the pivot of the hook-bending die for imparting rotary reciprocating motion to the latter bending-arm and die, substantially as set forth.

4. In a machine for bending the cross-heads and eyes of wire bale-ties, the combination of a shaft, a supporting-plate attached to the head of said shaft, a treadle-actuated sliding sleeve splined to said shaft, wire-bending devices arranged on said supporting-plate, means interposed between said wire-bending devices and sliding sleeve for operating the same, a spring-actuated counter-plate mounted on one of the pivots of the bending devices, means for imparting lateral motion to the counter-plate toward the supporting main plate for holding the wire during the bending operation and return the counter-plate to its former position for removing the bent wire, substantially as set forth.

5. In a machine for bending the cross-heads and eyes of wire bale-ties, the combination of a shaft, a treadle-operated sliding sleeve splined to said shaft, a supporting-plate attached to the head of said shaft, said plate being provided with a rim recessed at its upper part, wire-bending devices pivoted to said supporting-plate, means interposed between the sliding sleeve and said bending devices for operating the latter, a spring-actuated counter-plate guided on one of the pivots of the bending devices, means for guiding said counter-plate on the supporting main plate, and means actuated by the sliding sleeve for imparting lateral motion to said counter-plate during the wire-bending operation, substantially as set forth.

6. In a machine for bending the cross-heads and eyes of wire bale-ties, the combination of a shaft, a supporting-plate attached to the head of the shaft, a treadle-actuated sliding sleeve splined to said shaft, a bending-arm pivoted to said supporting-plate and provided with a pin at its outer end, a center pin in the pivot of the bending-arm, a second pin on said bending-arm eccentrically to said center pin, a stationary pin on the supporting-plate located opposite to the bending-arm, a recessed hook-bending die pivoted to the supporting-plate below the pivot of the bending-arm, and means between the pivots of the bending-arm and hook-bending die and the sliding sleeve for producing the movement of the bending-arm ahead of the movement of the hook-bending die and in an opposite direction to the latter, substantially as set forth.

7. In a machine for bending the cross-heads and eyes of wire bale-ties, the combination of a shaft, a supporting-plate attached to the head of said shaft, said supporting-plate being provided with a rim recessed at its upper end, a treadle-operated sliding sleeve splined to said shaft, a bending-arm pivoted to said supporting-plate and provided with a pin at its outer end, a center pin in the pivot of the bending-arm, a second pin on said bending-arm eccentrically to said center pin, a stationary pin on the supporting-plate opposite to the bending-arm, means between the pivot of the bending-arm and the sliding sleeve for operating the bending-arm, a hook-bending die pivoted below the bending-arm, means for moving said die in a direction opposite to the movement of the bending-arm, a spring-actuated counter-plate guided on the pivot of the hook-bending die, means for guiding said counter-plate on the main supporting-plate, and means for imparting lateral motion to said counter-plate so as to hold or release the bent wire, substantially as set forth.
8. In a machine for bending the cross-heads and eyes of wire bale-ties, the combination of a shaft, a supporting-plate attached to the head of said shaft, said supporting-plate being provided with a rim recessed at its upper end, a treadle-operated sliding sleeve splined to said shaft, a bending-arm pivoted to said supporting-plate and provided with a pin at its outer end, a center pin in the pivot of the bending-arm, a second pin on said bending-arm eccentrically to said center pin, a stationary pin on the supporting-plate opposite to the bending-arm, means between the pivot of the bending-arm and the sliding sleeve for operating the bending-arm, a hook-bending die pivoted below the bending-arm, means for moving said die in a direction opposite to the movement of the bending-arm, a spring-actuated counter-plate guided on the pivot of the hook-bending die, pins on said counter-plate guided in sockets of the supporting main

plate, a cam on the counter-plate, a second cam mounted on the pivot of the die, and means for operating one of said cam-surfaces so as to impart a lateral movement to said counter-plate, substantially as set forth.

50

9. In a machine for bending the cross-heads and eyes of wire bale-ties, the combination of a shaft, a supporting-plate attached to the head of said shaft, wire-bending devices on said supporting-plate, a spring-actuated counter-plate sidewise of said supporting-plate, means for imparting laterally-reciprocating motion to said counter-plate for holding or releasing the wire to be bent, clamping-jaws arranged in line with said wire-bending devices, means for clamping the wire after the same has been bent by the bending devices, and means for imparting a rotary motion to the shaft and the bending devices supported at the end of the same for twisting the bent end 65 of the wire blank, substantially as set forth.

55

10. In a machine for bending the cross-heads and eyes of wire bale-ties, the combination of a shaft, a supporting-plate attached to the head of said shaft, wire-bending devices located on said supporting-plate, means for operating said wire-bending devices, a spring-actuated counter-plate located sidewise of the supporting main plate, means for imparting lateral motion to the same for holding the wire 75 during the bending operation, clamping-jaws arranged in line with the wire-bending devices, means between the shaft and the clamping-jaws for clamping the latter to the wire after the same has been bent, and means for imparting a predetermined number of rotations to the shaft and bending devices for twisting the bent end of the wire blank, substantially as set forth.
